UNITED STATES PATENT OFFICE

HARRY R. McDONALD, OF DUNKIRK, INDIANA, ASSIGNOR TO HART GLASS MANUFACTURING COMPANY, OF DUNKIRK, INDIANA, A CORPORATION OF INDIANA

DESIGN FOR A CRUET OR SIMILAR CONTAINER

Application filed March 28, 1932. Serial No. 43,304. Term of patent 7 years.

To all whom it may concern:

Be it known that I, HARRY R. McDONALD, a citizen of the United States, residing at Dunkirk, in the county of Jay and State of Indiana, have invented a new, original, and ornamental Design for a Cruet or Similar Container, of which the following is a specification, reference being had to the accompanying drawings, forming part thereof.

Fig. 1 is a perspective view of the cruet showing my new design;

Fig. 2 is an elevation of the cruet illustrated in Fig. 1;

Fig. 3 is a transverse section on the line 3—3 of Fig. 2 illustrating the shape of the cruet in cross-section.

I claim:

The ornamental design for a cruet or similar container, as shown.

In witness whereof, I have hereunto set my hand at Dunkirk, Indiana, this 23rd day of March, A. D. one thousand nine hundred and thirty-two.

HARRY R. McDONALD.
